UNITED STATES PATENT OFFICE

PAUL BROCKHAUS, JR., OF OESTERAU IN WESTPHALIA, GERMANY

VISE

Application filed May 17, 1929, Serial No. 363,827, and in Belgium August 25, 1928.

My present invention relates to vises and has for its object to provide a vise of a considerably simpler and cheaper construction than has been possible hitherto. This end I attain by the use of a base-plate furnished with two guide-rails, of which each is provided with an approximately U-shaped lateral channel with oppositely arranged guide-surfaces for the slip-faces of pendent guide-cheeks of the vise-jaws. These guide-cheeks are on account of their novel attachment to the jaws to a certain degree resilient and thus adapted to automatically accomplish their readjustment on the worn guide-surfaces. But when the limit of this resilience has been reached the pendent guide-cheeks of the jaws are drawn inwards for a mechanical adjustment by means of adjusting-screws rotatably seated in said guide-cheeks and screwed into rectangular guide-blocks slidably arranged in slots of said guide-rails. Simultaneously herewith these guide-blocks serve to limit the outward movement of the vise-jaws when they strike against the closed ends of said slots.

My invention is applicable as well to vises with a fixed and a movable jaw as to vises with two movable jaws, i. e. to the so-called machine-vises. Between the two vertically arranged guide-rails a spindle provided with a right-hand and a left-hand screw-thread is arranged to move said jaws always simultaneously in opposite directions, whereby said spindle passes through the pendent nuts of both jaws and is held against axial displacement by a fixed arched abutment, which straddles said spindle between two collars of the latter.

A vise constructed in accordance with my present invention is shown by way of example in the accompanying drawings, in which:—

Figure 1 is a longitudinal section taken on line 1—1 of Figure 2.

Figure 2 is a plan-view of the improved vise.

Figure 3 is a cross-sectional view taken on line 3—3 of Figure 1, and

Figure 4 is a similar view taken on line 4—4 of the same figure.

The frame of the vise chiefly consists of a base-plate 1 whereon two guide-rails 2 are arranged parallel to each other and integrally connected to said base-plate. These rails are also connected with each other by cross-bars 3 and an intermediate vertical wall 4. Each rail 2 is on its outer face provided with an approximately U-shaped lateral channel 2' with oppositely arranged guide-surfaces 5, which may be arranged parallel to each other but preferably converge inwardly, i. e. transversely of said channels, and are carefully machined to serve as guide-ways for the vise-jaws 6, of which each is provided with pendent guide-cheeks 7. These guide-cheeks solely bear on said guide-surfaces 5 to leave gaps or air-spaces 8 between the under-sides of the vise-jaws 6 and the webs and top-portions of the rails 2, as clearly shown in Figures 3 and 4. The inclined guide-surfaces 5 thus obtained are designed to reduce the friction between them and the slip-faces of the pendent guide-cheeks. Simultaneously herewith the pendent guide-cheeks 7 are made resilient by the aid of the reduced web-like necks 7' connected with the under-side of the jaws, by means of which said pendent cheeks are enabled to take up wear to a certain degree quite automatically. When, however, the wear has reached a certain limit the adjustment is regulated mechanically by means of adjusting-screws 9, which are rotatably seated in said guide-cheeks 7 and screwed into internally threaded guide-blocks 10 seated in slots 11 of the rails 2 and protected against filings and dirt by shoulders 2'' of the guide-rails 2, as indicated in Figures 3 and 4. The adjustment thus obtainable can be conveniently executed on account of the exposed position of the heads of the adjusting-screws 9 and may be applied to either of the guide-cheeks of each jaw 6 alone or to both jaws simultaneously.

The movement of the vise-jaws 6 to and from each other is accomplished by means of a spindle 12 provided with a right-hand and a left-hand screw-thread, which engage the pendent nuts 13 of said jaws. These nuts are fitted into said jaws and retained therein in their proper positions by screws 14. The

spindle 12 is sustained at 4' in said intermediate wall 4 and besides this is straddled by an arched abutment 15 which enters between the collars 16 and 17 integrally connected with said spindle. To prevent an axial displacement of the spindle said arched abutment is inserted into vertical slots 18 of the rails 2 and held in place therein by screws 19, as clearly shown in Figure 3. 10 Cover-plates 20 and 20' are attached to the jaws 6, of which plates the cover-plates 20 cooperate with a plate 21 secured to the top of the arched abutment 15 to form a cover of variable length, which at all times forms an effective means for the exclusion of filings and dirt from the spindle 12.

The improved vise is of an exceptionally small height and of a very simple construction and can on these accounts be manufactured at a lower cost than the known, mostly rather complicated vises of this class. In operation this new vise is reliable since the inclined guide-surfaces of the guide-rails and the slip-faces of the resilient guide-cheeks of the jaws coact under the most favorable conditions and besides this these bearing-faces are always protected by the top-members of the guide-rails.

I claim:—

30 1. A vise, comprising a base-plate, guide-rails arranged on said base-plate parallel to each other and provided each with an approximately U-shaped lateral external channel having oppositely arranged guide-surfaces, a pair of vise-jaws movably seated on said guide-rails, pendent guide-cheeks arranged on the under-side of said vise-jaws and solely bearing on said guide-surfaces, pendent nuts on said vise-jaws, and a spindle adapted to move said vise-jaws simultaneously in opposite directions.

45 2. A vise, comprising a base-plate, guide-rails severally arranged on said base-plate parallel to each other and each provided with an approximately U-shaped lateral external channel having oppositely arranged bearing-surfaces, a pair of vise-jaws movably seated on said guide-rails, pendent guide-cheeks resiliently connected with the under-side of said vise-jaws and solely bearing on said guide-surfaces, pendent nuts seated in said vise-jaws and projecting between said guide-rails, a spindle engaging said pendent nuts and adapted to move said vise-jaws simultaneously in opposite directions, and a U-shaped abutment seated in said guide-rails and straddling said spindle between collars of said spindle to prevent axial displacement of the latter.

50 3. A vise, comprising a base-plate, guide-rails severally arranged on said base-plate and each provided with an approximately U-shaped lateral external channel with oppositely arranged guide-surfaces converging inwardly, a pair of vise-jaws movably seated

on said guide-rails, pendent guide-cheeks resiliently connected with the under-side of said vise-jaws and solely bearing on said inwardly converging guide-surfaces, means for independently adjusting both guide-cheeks on the guide-surfaces of said lateral rail-channels, pendent nuts removably seated in said vise-jaws, a spindle having right-hand and left-hand screw-threads engaging said pendent nuts for moving them simultaneously in opposite directions, a pair of collars integrally connected with said spindle, and a U-shaped abutment removably seated in said guide-rails and straddling said spindle between two collars integrally connected with said spindle.

4. A vise, comprising a base-plate, guide-rails integrally connected with said base-plate and at one end with an intermediate wall and each provided with an approximately U-shaped lateral external channel with oppositely arranged guide-surfaces, a pair of vise-jaws movably seated on said guide-rails, pendent guide-cheeks secured by reduced web-like necks to said jaws to make them adapted to resiliently seat themselves solely on the guide-surfaces of said guide-rail channels, internally threaded guide-blocks operating in longitudinal slots of said guide-rails, adjusting-screws rotatably seated in said guide-cheeks and screws into said guide-blocks for mechanically adjusting said guide-cheeks, pendent nuts seated in said vise-jaws, a spindle having right-hand and left-hand screw-threads engaging said pendent nuts and sustained on one end by said intermediate wall, and an arched abutment detachably connected with said guide-rails and straddling said spindle between two collars forming integral parts of said spindle to protect the latter against axial displacement.

In testimony whereof I affix my signature.
